AXEL BREMBERG, OF GLASGOW, SCOTLAND.

HYDRAULIC RECOIL APPARATUS FOR ORDNANCE.

1,398,172.

Specification of Letters Patent. Patented Nov. 22, 1921.

Application filed June 24, 1920. Serial No. 391,299.

To all whom it may concern:

Be it known that I, AXEL BREMBERG, of Parkhead Forge Rolling Mills and Steel Works, in the city and county of Glasgow, 5 Scotland, engineer, have invented certain new and useful Improvements in Connection With Hydraulic Recoil Apparatus for Ordnance, of which the following is the specification.

10 The invention relates to hydraulic recoil apparatus for ordnance of the kind in which the recoil and return of the gun is controlled by the passage of liquid through apertures, and has for its object to provide improved 15 valve devices for so controlling these apertures that the movement of the gun, particularly during its return to firing position, is as rapid as may be, while at the same time it is so gradually checked that it comes to 20 rest without shock.

According to the invention, while the flow of liquid under the moment of recoil is jointly controlled in known manner by constant leakage apertures and by a valve disposed 25 in the annulus between the usual piston rod and the recoil cylinder in which it operates and so spring-loaded as to open under the moment of recoil but remain closed during the return movement of the 30 gun, the return movement of the gun is controlled jointly by constant-leakage apertures and by another valve, also located in the annulus between the piston rod and recoil cylinder and closed during the recoil, but 35 so spring-loaded that during the return movement it opens at the beginning of that movement and while the pressure in the liquid is high, but is closed against that pressure by the action of the spring when the 40 pressure falls to a predetermined point and remains closed for the remainder of the return movement. Thus, as the liquid passes through both the constant leakage and the valve-controlled apertures during the first 45 part of the return movement, that part of the movement may be very rapidly performed, but as the valve closes with the fall of pressure, the available area for the passage of liquid becomes less and less, and 50 thus the speed of return gradually diminishes and the gun is finally brought to rest without shock although the return movement as a whole is very rapid.

An illustrative example of the carrying 55 out of the invention as applied in the recoil

apparatus forming the subject-matter of the prior U. S. Patent No. 1,385,301 is shown in longitudinal sectional elevation in Figure 1 of an accompanying sheet of explanatory drawings, Figs. 2 and 3 thereof being views 60 at right angles to one another of a detail.

In this example, the parts are arranged in the annular space between the piston rod A and the cylinder B in which it moves. The valve opening under the moment of recoil 65 is of annular form and is shown separately in section and in elevation respectively in Figs. 2 and 3. It consists of a sleeve-like part C sliding upon the piston-rod A and an annular face part D which coacts with a seat 70 formed upon the inner periphery of a sleeve E fixed in the cylinder B. A helical spring F in compression between the valve and the cylinder end holds the valve on its seat. Constant leakage grooves G are formed 75 across the face of the part D so that liquid flowing through the annular space between the piston rod A and the sleeve E has access through the grooves to the space beyond.

Through the sleeve E and radially beyond 80 the valve seat is an annular series of apertures H. These apertures at the end of the sleeve E remote from the recoil valve are closed by an annular valve J held up against the end of the sleeve E by a spring K in 85 compression between it and an inturned flange on a sleeve L fixed in the cylinder B. This device forms the valve closed during recoil but opening under the initial heavy pressure of the return movement, and the 90 spring K loading it is of such strength and is so adjusted that it forces the valve J back upon its seat on the end of the sleeve E, so closing the annular series of apertures H when the pressure of return falls to a pre- 95 determined point, thus reducing the area available for the flow of the liquid and thus checking the speed of return, and finally bringing the gun to rest without shock.

What I claim is:

1. In hydraulic recoil apparatus for ordnance, in combination constant leakage apertures and a valve so disposed and so spring loaded as to open under the moment of recoil but to remain closed during the return movement and a second valve controlling the return movement, closed during recoil, but so spring-loaded that it opens at the beginning of that movement but gradually closes and remains closed during the latter part of the 110

return movement both valves being located in the annulus between the piston rod and the recoil cylinder in which it operates, as and for the purposes set forth.

5. 2. In hydraulic recoil apparatus, a ported sleeve fixed in the recoil cylinder and located in the annulus between the piston rod and the recoil cylinder in which it operates, an annular valve controlling said ports, and a

spring pressing said valve to closure position 10 so that while the valve moves to open the ports during the initial part of the return movement, it thereafter gradually closes and remains closed for the latter part of that movement.

15

In testimony whereof I have signed my name to this specification.

AXEL BREMBERG.
